UNITED STATES PATENT OFFICE.

ELEUTHERE PAUL DU PONT, OF WILMINGTON, DELAWARE.

MACHINE FOR ATTACHING HOOKS AND EYES TO CLOTH.

1,102,021.

Specification of Letters Patent. Patented June 30, 1914.

Application filed November 5, 1912. Serial No. 729,569.

To all whom it may concern:

Be it known that I, ELEUTHERE PAUL DU PONT, a citizen of the United States, residing at Wilmington, county of Newcastle, 5 and State of Delaware, have invented a new and useful Improvement in Machines for Attaching Hooks and Eyes to Cloth, of which the following is a full, clear, and exact description, reference being had to the 10 accompanying drawings, which form a part of this specification.

The object of my invention is to secure hooks and eyes to clothing, etc., with maximum rapidity and to this end it consists of 15 a machine, adapted to operate upon an integral strip of hooks provided with prongs, in such manner that, at each single operation, a hook will be cut off and securely fastened to the cloth.

20 A preferred construction of the machine is illustrated in the drawings and particularly described in the following specification, while the particular combinations of elements constituting my invention are re- 25 cited in the claims.

Figures 1 and 2 are longitudinal sectional elevations of the machine with the parts in different positions. Fig. 3 is an enlarged detail view of the holding cam in engagement with the strip of hooks. Figs. 4 and 5 are cross-sections on the line 4—5 of Fig. 2; Fig. 4 showing a section through a strip of hooks and Fig. 5 showing a section through a strip of eyes. Fig. 6 is a perspective view 35 of one of the hooks detached from its strip. Fig. 7 is an inverted plan view of a part of a strip of hooks. Fig. 8 is a perspective view of one of the eyes detached from its strip. Fig. 9 is an inverted plan view of a 40 part of a strip of eyes.

a, a, a, etc., represent a series of hooks, the same being integrally attached together to form a strip of hooks of convenient length.

45 *b, b, b, etc.*, represent a series of eyes, the same being integrally attached together to form a strip of eyes of convenient length.

The specific constructions of these hooks and eyes may be varied from those shown, as 50 they form no part of the invention claimed herein. It is necessary, however, that they be provided with prongs, as, for example, those marked *c*, which the machine is adapted to force through the cloth and bend down

against the inner face of the cloth, as will 55 be hereinafter described.

On the base *d* of the machine are a pair of standards *e* through which extend the cross-pins *f* and *g*. The base *d* has an anvil *d'*. Hinged on the pin *f* are the pieces or 60 arms *h* and *k*. The piece *h* carries the holding pawl *i* and the stop *j*. The piece *k* carries the hammer *l* and the hand-hit *m*. A spring *t* is confined between the base *d* and the piece *k*, and thus holds it in its 65 raised position. The piece *k*, which is trough shaped, extends under, as well as in opposite sides, of the piece *h*, and normally supports it, also, in its raised position. Hinged on the cross-pin *g* is the feeding 70 pawl *n*. A spring *o* is secured to the piece *h* and engages the pawl *n* and holds it depressed. A spring *p* is confined between the piece *h* and the hand-hit *m*.

The strip of hooks (or eyes) is inserted 75 into a longitudinally-extending closed channel guide *r* formed in the piece *h*. The upper wall of the channel guide is cut away to receive the pawls *i* and *n*. The forward end of the guide terminates immediately behind 80 the hammer *l*. The strip of hooks is pushed forward until the hook at the front extends immediately under the hammer *l*. Its accurate positioning is insured by the holding pawl *i*, which, as shown in Fig. 3, is so 85 shaped that its front portion extends between, and fills the space between, the bills of two adjacent hooks. The widened front part of the pawl *i* is so shaped as to abut against the bill of one hook and positively 90 hold the strip from slipping backward. The rear end of this widened front portion is beveled so as to hold the pawl from accidentally slipping forward but not so as to prevent its forward movement when it is 95 positively pushed forward, as hereinafter described, by the feeding pawl *n*. A spring *s*, secured to the piece *h*, bears against the pawl *i* and normally holds it down in operative position. A strip of hooks is fed 100 into the guide *r* and is properly positioned and engaged by the pawls *i* and *n*, as above described and as shown in Fig. 1. The cloth is placed on the anvil *d'*. With the hand a blow is struck upon the hand-hit *m*. The 105 hammer *l* strikes the first hook and thus carries the piece *h* down with it and against the anvil. The piece *h* immediately rebounds,

and this upward movement relatively to the hammer *l* severs the front hook. The hammer *l*, as soon as the hook is severed, is released from effective connection with the piece *h*, and it continues to descend, carrying the hook with it, since the latter has not time to fall away or become displaced. The hook is therefore forcibly driven against the cloth and the anvil *d'* and the prongs *c* are forced through the cloth and clenched. However, due to the recess *v* in the striking face of the hammer *l*, the bill of the hook is not closed or deformed, but remains open for use. During the downward stroke of the pieces *h* and *k*, the feeding pawl *n* has moved on its axis so that its actuating end has slipped over and engaged the bill of the next hook. As soon as the hand is removed, the piece *k* rises by the action of springs *t* and *p* leaving the piece *h* pressed down against the anvil by the action of the spring *p*. However, as soon as the lower wall of piece *k* strikes the piece *h*, the spring *p* can have no further action and the hammer *l* will have cleared the end of the guide *r*. Piece *k* continues to rise under the action of spring *t*, carrying with it the piece *h*, until the stop *j* abuts against the rear part of the base *d*. This action causes the feeding pawl *n* to return to the position shown in Fig. 1, thus feeding the strip of hooks forward and bringing another hook under the hammer *l*. The parts are so proportioned that the strip will be fed forward precisely the distance of the width of one hook, this being further insured by the action of the holding pawl *i*.

Having now fully described my invention, what I claim and desire to protect by Letters Patent is:

40 1. In a machine for severing hooks and eyes from a strip and applying them to garments, the combination with an anvil, of two movable arms pivoted at their rear end portions, the first arm having a guide for the strip, a hammer carried by the second arm at its front end portion, a spring normally holding the second arm in its raised position, the second arm having, between its pivotal support and the hammer, a base extending under and arranged to normally hold the first arm in its raised position, side pieces extending on opposite sides of the first arm, a spring between the hammer and the first arm, and means to feed and position 55 the strip.

2. In a machine for severing hooks and eyes from a strip and applying them to garments, the combination with an anvil, of a pair of standards, a pair of cross pins between the standards, two arms hinged at their rear on one of said cross pins, one of said arms having a longitudinal strip guide between its upper and lower faces, a hammer on the second arm extending beyond the 65 front end of the first arm, a pawl pivoted

on the other cross pin and extending through a cut-away part of the strip guide and having a feeding end arranged for operative engagement with the strip, and means normally holding both of said arms in a raised position but permitting said arms to move relatively to one another on their axis. 70

3. In a machine for severing hooks and eyes from a strip and applying them to garments, the combination with two movable arms pivoted at their rear end portions, the first arm extending near its pivoted end under and supporting the second arm and extending at its front end over the second arm, of a hammer on the first arm extending in front of the second arm, said hammer having a hand-hit, a spring supporting the first arm independently of the second arm, a spring between the second arm and the hammer, and an anvil under the hammer 85 and the front end of the second arm, whereby when the hand-hit is struck the hammer will, by its engagement with the projecting end of the strip, depress the second arm against the anvil and cause it to rebound and 90 sever the strip while the hammer continues its descent and secures the detached hook to the cloth, and strip-feeding mechanism arranged to be actuated in the movement of said arms. 95

4. In a machine for severing hooks and eyes from a strip and applying them to garments, the combination with an anvil, of two arms pivoted at their rear ends on a common axis, one arm having a strip guide, a hammer on the second arm arranged relatively to the guide so as to engage one of the units of the strip and thereby, when moved toward the anvil, depress the strip and the first arm, a base arranged to arrest the downward movement of the first arm and thereby, as the hammer continues its downward movement, cause said unit to be severed, means to return both arms to their raised position upon release of downward pressure against the hammer, and means operated in the return movement of the arms to feed the strip forward. 100 110

5. In a machine for severing hooks and eyes from a strip and applying them to garments, the combination with a base and an anvil thereon, of two arms hinged on a common axis, the second arm having a part underlying a part on the first arm and thereby normally holding the latter in a raised position, the first arm having a longitudinal strip guide, a spring confined between the base and the second arm, and normally holding it in a raised position, a hammer on the second arm arranged relatively to the guide 115 so as to engage one of the units of the strip and thereby, when moved toward the anvil, depress the strip and the first arm and thereby, as the hammer continues its downward movement, cause said unit to be severed, a 120 125 130

spring between the hammer and the second arm, a feeding pawl pivotally connected with the base and arranged, in the downward and upward movement of the first arm, 5 to slide back relatively to the strip and then move the strip forward, and a holding pawl coöoperating with the feeding pawl to position and hold the strip.

In testimony of which invention, I have hereunto set my hand, at Wilmington, Del., 10 on this 29th day of October, 1912.

ELEUTHERE PAUL DU PONT.
